FILTERING SYSTEM, DEVICE USED THEREIN, AND METHOD OF FILTRATION

William C. Laughlin, New York, N. Y., assignor, by mesne assignments, to W. C. Laughlin Corporation, Dover, Delaware, a corporation of Delaware

Application July 17, 1937, Serial No. 154,226

13 Claims. (Cl. 210—128)

This invention relates to filtration systems used in connection with the clarification of waters, sewage, industrial waste waters, etc., and has for its object to provide an improved system overcom-
5 ing the objections to those heretofore proposed.

My improved system of filtration consists in subjecting a filter bed to a surface cleaning at periodic times, and to a deep cleaning at other times, the former depending on time intervals, and the
10 latter on head control, the injection of water with or without air being used in connection with such deep cleaning.

The invention consists further in the novel de-
15 vices employed in carrying out the improved sys-
tem, first, in the provision of an improved surface
cleaning which consists in means riding along the
surface of the filter bed, means for removing im-
purities from the surface layer of the filter bed,
means for removing the impure water, and means
20 for returning any part of the filter bed removed
therefrom by the operation of the device. This
surface cleaning is carried out periodically at pre-
determined time intervals.

The invention consists also in the provision of
25 a deep cleaning device which plows into and
through the filter bed and subjects the entire fil-
ter bed to a cleansing of its parts, and, while this
plowing action proceeds, subjecting the filter bed
to the action of water preferably combined with
30 air so as to remove all impurities of the filter bed
constituents; means being provided to draw off
by siphoning action the water containing the im-
purities. In connection therewith, sand replen-
ishing means are provided to compensate for any
35 sand loss entrained with such impurities.

The invention consists further in means pro-
viding for the ready removal of the deep cleaning
device, and its replacement under the same ad-
justment conditions.

40 The invention consists further in providing a
pipe having perforations, at the lower part of the
filter bed to loosen the material of the filter bed
for permitting the descent of a deep cleaner
therethrough.

45 The invention consists still further in improved
methods of cleaning filter beds, which consist in
subjecting the top surface of the filter bed to agi-
tation for cleaning the same, removing therefrom
the impurities, and returning such portions of the
50 filter bed as have been cleaned to the filter bed
proper, with simultaneous removal of the water
containing the impurities.

The invention consists further in the method of
subjecting the entire filter bed to a localized agi-
tation action simultaneously with impingement

upon the constituents of the filter bed of cleaning
water, preferably with air, and removing the im-
purities from the filter bed.

A further method is the replenishment of the
filter bed by a supply of filter bed material as re-
quired, to supply filter bed material to the filter
bed so as to keep it at a constant level, in the
event there has been any loss due to wear or en-
trainment with the wash water.

These methods consist further in the steps of 10
subjecting the filter bed periodically to the sur-
face cleaning action, and periodically to the deep
cleaning action.

The invention will be further described herein-
after, embodiments thereof will be shown in the 15
drawings, and the invention will be finally pointed
out in the appended claims.

In the accompanying drawings:

Figure 1 is a side view of my improved filtra-
tion installation showing a broken-away portion 20
to indicate that the filtration tank may be of any
length;

Figure 2 is a horizontal section taken on line
2—2 of Figure 1;

Figure 3 is a vertical transverse section taken 25
on line 3—3 of Figure 1 and showing a side view
of the surface cleaner in its relation to the filter
bed;

Figure 4 is a vertical transverse section taken
on line 4—4 of Figure 3 showing the improved 30
device used for surface cleaning;

Figure 5 is a sectional view taken on line 5—5
of Figure 3 showing the valve which is operated
at each end of the run of the surface cleaner;

Figure 6 is a vertical transverse section taken 35
on line 6—6 of Figure 1;

Figure 7 is a vertical section taken on line 7—7
of Figure 6;

Figures 8, 9 and 10 show diagrammatically the
operation of the device, Figure 8 showing the sur-
face cleaning action, Figure 9 the deep cleaning
step, and Figure 10 the removal of the water with
the impurities after the deep cleaner in Figure 9
has churned up the filter bed, these views in
Figures 8, 9 and 10 being in transverse sections 45
of the installation.

Figure 11 is a plan view of the frame taken on
line 11—11 of Figure 6, which in its adjusted po-
sition can be removed and replaced in position, in
the event the deep cleaner is taken out for repair 50
or for any other purpose.

Figure 12 is a diagrammatic side view of the
filtrate and wash water pipes, shown as determin-
ing different levels than when in the position
shown in Figure 1; and

Figure 13 is a diagrammatic view of the action of the deep cleaner.

Similar characters of reference indicate corresponding parts throughout the various views.

Referring to the drawings, and more particularly to Figures 8 to 10, the installation there shown consists of a foundation portion 11 having a launder 12 at the left hand thereof, and a launder 13 at the right hand thereof. Intermediate of these two launders is a filter bed portion 14 in which the filter bed proper, 15, is supported by a screen 16 placed upon the abutments 17. The central portion 14 is supplied with the water to be filtered through a main supply pipe 18 having branch supply pipes 19 distributed along the length of the central portion 14. The outlet portion 20 of these supply pipes 19 are shown in Figures 8 to 10, and in the remaining figures they are shown as level with the level line 20 of the water in the central portion 14, this level line being indicated by the character 20a. The level of the water in the launder 12, and the level of the water in the launder 13, is indicated by the characters 12a and 13a. These levels 20a, 12a and 13a are shown in all of the drawings as indicative of the particular installation shown in these drawings, but they may be varied, as will be hereinafter more fully seen. It is desirable to raise the outlet ends 20 of the branch pipes 19 to as high a point in the central portion 14 as possible, though that part does not necessarily determine the level in the filter bed channel. The levels 12a and 13a are controlled by the position of outlet pipes which are in connection with the launders 12 and 13, and which outlet pipes have pipes at right angles to the outlet pipes, the pivotal position of these pivoted pipes enabling the levels 12a and 13a to be determined. The outlet pipe for the filtrate in launder 12 is best shown in Figure 2, and is indicated by 21; and the outlet pipe for the wash water of launder 13 is indicated by 22 in Figure 2. In Figure 12, these outlet pipes are shown diagrammatically in another position which, in consequence, determine other levels.

To the end of pipe 21 there is pivoted a short pipe 23 having an outlet portion 24. This pipe 23 is capable of being moved on its pivotal portion 25 from its horizontal position to a vertical position, and the height of the orifice or outlet 24 of pipe 23 determines the level 12a of the filtrate in the launder 12.

To the outlet pipe 22 a similar short pipe 26 is pivoted, which is shown in dotted lines in Figure 1, and its orifice 27 may be moved from its lowermost to the highest position, in a manner similar to the action of the pipe 23, and the position of the orifice 24 determines the level 13a of the wash water in launder 13.

Referring again to Figure 8, there is arranged below the filter bed 15 an enlarged channel 30 through which the filtrate passes and escapes through pipes 31 into the launder 12. With a construction as just described in connection with Figure 8, my improved surface cleaner, indicated in general by the character 32, is placed upon the top surface of the filter bed 15 and moved longitudinally along the same, and as the cleaning action of the surface of the filter bed takes place due to the operation of this surface cleaner 32, the water with impurities is siphoned up through the pipe 33 and discharged at the outlet orifice 34 arranged below the level 13a in the launder 13. The movement of this water with impurities is indicated by the small arrows,

whereas the movement of the body of the water that is being filtered as it passes through the filter bed proper, enlarged channel 30, pipe 31, into the launder 12, is indicated by the larger or tailed arrows.

It will be seen from Figure 8 that the operation there shown is for the purpose of subjecting the topmost layer of the filter bed proper to a surface cleaning action whereby the accumulated impurities upon the filter bed proper are removed. Such impurities are algae, amorphous matter, etc. The to and fro movement of the surface cleaner 32 brings about this surface cleaning action of the filter bed. This longitudinal movement of the surface cleaner is carried out periodically in predetermined time intervals by a motor operated travelling carriage.

In certain cases, however, it is desirable to subject the filter bed itself to a thorough cleaning. For this purpose, there is shown in Figure 9 the deep cleaner indicated in general by 35, which in passing longitudinally through the filter bed from one end of its length to the other, plows, so to say, the entire contents of the filter bed, and by this plowing action, all the loosened particles of foreign matter adhering to the constituents of the filter bed are removed therefrom by the action of water, or water and air, the air being preferably in aspirated form, acting in the form of a series of jets against the constituents of the filter bed so as to loosen all of the adhering particles.

As seen from Figure 9, there extends into the filtrate launder 12 a vertical pipe 36, into which there is sucked by a pump 37 a part of the filtrate in the launder 12, and this clean water or filtrate is forced, as indicated by the arrows, into the two branch pipes 38. Each of these branch pipes 38 has an air inlet pipe 39, and the movement of the water through the depending pipes 40 sucks in a certain amount of air which mixes with the water and is then ejected out of the deep cleaner 35. This water, with or without air, subjects the filter bed to a thorough upwardly-moving cleaning action.

Should any sand or the like, constituting the filter bed, be drawn up with the water containing the impurities, a provision is made for the replenishing of sand to the filter bed by means of a sandbox 46 containing sand, 46b, as shown in Figure 10. This sandbox 46, in passing over the filter bed 15, always maintains the filter bed at a constant level, since sand passes through the openings 46a of the sandbox when the level of the filter bed is below the bottom surface of the sandbox. (See Figure 1.)

The action of removing the wash water with the impurities stirred up by the deep cleaner 35, takes place simultaneously with the churning up of the filter bed by means of the device 42, and for this purpose the removal device 42 shown in Figure 10 is provided. This device 42 is placed above the deep cleaner 35, as shown in Figure 7, and these in turn are adjacent the sandbox, as shown in Figures 1 and 2, but for clarity in respect to their operations, are shown diagrammatically in separate figures, namely, Figures 9 and 10.

While the plowing action takes place, together with the impingement of the water and air jets, 70 if used, upon the constituents of the filter bed in a relatively localized manner, the churned up and rather ebullient water is captured by an enclosing casing having an open bottom, as shown in Figure 6. This water containing the impuri- 75

ties is then, by a siphoning action acting upon the removing device 42, shown in Figure 10, drawn through openings 43 of the removing device 42, and, as shown by the arrows, is siphoned upwardly through the pipe 44 which has its discharge orifice 45 in the launder 13 below the water level 13a, as shown in Figure 10.

From the foregoing, it will have been seen that if only a surface cleaning is desired, the device 10 32 is moved periodically longitudinally along the top surface of the filter bed, in accordance with a predetermined time element. Should it be desired to subject the entire filter bed to a thorough cleaning, then the deep cleaning device 35, with 15 the wash water removing device 42 and sand replenishing device 46, is set into operation, which may be done also periodically, but preferably dependent upon a predetermined head or level above the filter bed.

20 Referring now to Figures 1 and 2, it will be seen that at the left hand side of these figures the surface cleaning device is shown, and on the right hand side of these figures the deep cleaning device is shown. While these figures 25 only show one surface cleaning device and one deep cleaning device, it is, of course, clear that one deep cleaning device can be used with two surface cleaning devices, the deep cleaning device in this case being intermediate of the two 30 surface cleaners.

Referring now to the left hand portions only of Figures 1 and 2 and to Figures 3, 4 and 5, the surface cleaning device will be described.

In Figure 4, the level of the filter bed 15 is 35 indicated by the surface 15a. Along this surface there is passed a surface cleaner indicated in general by 32, which consists of a suspended shoe 50 having tapering or sharpened edges 51 and 52. These edges 51 and 52 enter a very small 40 distance below the surface of the filter bed. Since the main object is to remove the scum or layer in the form of algae, amorphous matter, etc., resting upon the filter bed, but as such scum or layer may adhere to the topmost particles, the 45 shoe enters below these topmost particles, entering a fraction of an inch below the level 15a.

Assuming the movement of the surface cleaner 32 to be from left to right of Figure 4, as indicated by the arrow 53, then the superimposed 50 layer of scum or the like and the topmost particles of sand of the filter bed, if the filter bed be of sand, is forced into the channel 54, and due to the rotation of the fan member 55, having blades 56, in the direction of the arrow 57, the 55 water with the impurities, and perhaps a minor quantity of sand, is forced upwardly by the rotary direction of the arrow 57 and subjected to a churning action thereby, and finally is discharged into the enlarged cavity 58, which, due to the 60 rotation of the blades 56, is generally kept in agitation. The heavier particles, such as the sand or other filtering material, descend by gravity into the spaces between the blades 56 and are discharged upon the filter bed. As a result of 65 this action, any sand particles of the filter bed are again returned to it, and the filter bed remains at its constant and desired level. The water with its impurities, however, is siphoned through the orifice 60 into the pipe 33, and is 70 discharged into the wash water compartment 13, as described in connection with Figure 8. The major part of the sand passes over the shoe 50, and is paddled by the blades 56 over the shoe 50 and descends on the downward slope 51, as it 75 ascended on the upward slope 52.

The surface cleaner 32 is suitably supported by providing the same with brackets 61 through which screw-threaded parts 62 of rods 96 pass, which extend upwardly to a movable platform 65, adjustment of such rods being possible through 5 nuts 63, as also by screw-threads 97 and nuts 98.

The platform 65, shown best in Figures 1 to 3, is supported upon wheels 66 on an axle 67, which wheels move upon rails 67a of the side tank walls 68 of the filter bed launder. 10

Upon the platform 65 there is also arranged an electric motor 68, the shaft 69 of which has a gear wheel 70 over which a drive chain 71 passes, which in turn passes over a gear or sprocket wheel 72 secured to a shaft 73 upon which the fan member 55 is secured, as shown in Figure 4. Thus, the rotation of the motor 68 causes a rotation of the fan member 55. The motor shaft 69 has a second sprocket wheel 74 which moves a larger sprocket wheel 75 by means of a chain 76. The 20 sprocket wheel 75 is keyed to the shaft 67, and moves the same. It will be seen, therefore, that the rotation of the motor in one direction rotates the fan member 55 in one direction and also moves the platform 65 in one direction. 25

After the platform 65 has reached one end of its travel on the rail 67a, it becomes necessary to reverse the action of the motor 68 and the rotation of the fan member 55 and the direction of movement of the platform 65. 30

The pipe 33 of Figure 8 is provided at its lowermost end with a valve operating weighted member 77 which at one end of the movement of the platform 65 strikes the rod 78, shown in Figure 1. This valve is shown in detail in Figure 5 where it is seen that the weighted member 77 is pivoted at 79 and has a valve member 80. When the valve member 80, with its depending portion 77, is in the vertical position shown in full lines, Figure 5, the channel 81 has a clear passage from the pipe 40 33 to the pipe 33a, and the wash water descending in pipe 33 can pass through the channel 81 into the pipe 33a up to the T-member 33b from which it is discharged from its orifice 34 into the launder 13. The extension of the pipe 33a indicated by 83 in Figure 1, is a pipe having no function excepting to balance the forces in supporting the valve device shown in Figure 5. If a pipe is used, it is capped, as shown by 84 in Figure 1. Instead of a pipe which is capped, a solid rod 50 can be used. The utilization of either a capped, hollow rod or a solid rod saves in material, since the valve device could be supported equally well by a stronger pipe than that indicated by pipe 33. As the platform 65 moves longitudinally over 55 the filter bed with the surface cleaner 32 in action, the weighted member 77 takes the position as shown in full lines in Figure 5. When, however, the member 77 strikes the cross rod 78, then the member 77 is thrown into the position as 60 shown in dotted lines and indicated by 77a. The valve 80 then closes the channel 81 and prevents any further passage of fluid therethrough. When the motor is reversed in its direction of rotation and thereby the platform is moved in the opposite direction, the rotation of the fan member 55 is in opposite direction, and the weighted member 77a being released falls back to its full line position as shown in Figure 1, and the fluid can pass through the channel 81 and be discharged out of 70 the orifice 34 of the T-member 33b. 65

When the platform 65 reaches the extreme position at the other end of the filter bed, the member 77 will strike either against a small rod similar to the cross rod 78 at that end of the filter 75

bed, not shown, or strike against a spray pipe 85 extending across the filter bed and in the path of the weighted arm 11, and thereby the member 11 is thrown into the position shown in dotted lines and indicated by 11b.

It will be noted from Figures 1, 2 and 3 that the water supply pipe 18 extends longitudinally along the filter bed and is provided with upright branch pipes 19 arranged along the length of the filter bed having their orifices 20 at such level as may be decided upon. The water supply pipe 18 is controlled by a hand operated valve 86, as shown in Figure 2, and is capped by a cap 87 at the other end of the filter bed, as shown in Figures 1 and 2.

Throughout the length of the filter bed, the filtrate discharge pipes 31 are arranged, as shown in Figure 1, which conduct the filtrate into the filtrate launder 12.

In the pipe 33 as shown in Figure 3, a check valve 88 is shown which is preferably placed as close as possible to the surface cleaner 32. The position of the surface cleaner may be adjusted due to the screw-threaded portion 97 of the supporting rods 96 and nuts 98, and correspondingly pipe 33 through 89a and 90, and part of the pipe 33, the horizontal portion 91, is made of flexible metal hose so as to take care of the variations in adjustment. A union joint 150 is provided therein to enable the hose to be separated. Extending upwardly of the T-joint 92 of this flexible hose 91 and the depending pipe 33, there is a pipe 93 with a gate valve 94 having an open end 95. This open end 95 and the gate valve 94 are used for priming the operation when the apparatus is first set into operation after standing idle, after which the valve 94 is closed and the siphoning effect described is automatic.

The deep cleaner and sand replenisher are shown in the right hand side of Figures 1 and 2, as also in Figures 6 and 7. Referring particularly to Figure 7, it will be noted that the screen 16 supports the filter bed proper, 15, and that close to the surface of the screen 16 there are arranged two plow-like members 100, each pointing in an opposite direction. The plow-like member 100 is supported by vertical pipes 101, which in turn supports a transverse or horizontal pipe 102. This pipe 102 has at its bottom a larger opening 103, and throughout its circumference a plurality of smaller openings 104. The pipes 101 extend upwardly into larger pipes 40, and may be coupled thereto by suitable couplings 106. These pipes 40 extend vertically upward to the branch pipes 38 and receive water from the pump 37, as explained in connection with Figure 9, receiving air at the same time through the aspirator pipes 39.

Referring again to Figures 7 and 13, if the deep cleaner be moved from left to right in the direction of the arrow 169, the filter bed material will be caused to slide along the inclined surface 105, and become subjected to the action of water, or water and air, as shown in Figure 13. The space between the curved surface 106 and the plow 100 and the pipe 102 forms a channel 107, and is subjected to water and air jets and keeps the filter material from entering therethrough. As the filter bed particles flow in the direction of the lines 170 (see Figure 13) and thus pass over the pipe 102, they are subjected to the sprays of cleaning water and air passing out of the pipe 102. Thereby, all the aggregated impurities of the filter bed particles are loosened and removed therefrom, and these

ascend as shown by the arrows 111 in Figure 13 upwardly through the filter bed with the water and air entraining the same, the air causing an upward ebullition, bounded by the outward bubbles 112 (see Figure 13), and are captivated by a casing 110 having an open bottom 111, and ascend in this casing upwardly until they strike a plate 112, and in passing around this plate 112 they are siphoned by the removal device 42 generally described in connection with Figure 10. This device, as shown in Figure 7, consists of two longitudinal pipes 42a having openings 43 through which the fluid with the impurities is siphoned upwardly through the pipe 44 through its flexible connection 44a having a union joint to enable separation thereof, and down through pipe 44 into the wash water launder 13.

Upwardly extending from the T-joint 44b of the flexible hose 44a is an upright pipe 115 having a gate valve 116 and an open orifice 117, said open orifice and gate valve being used to prime the operation when the apparatus is set into action. After it has once been primed, the siphoning action is automatic.

The pipes 40 may be vertically adjusted by means of the screw-threaded portions 118 and nuts 119.

The deep cleaner 35 and removal device 42 are supported by a plate 155 on a platform 120 which, in turn, may be adjusted by the adjusting means 121 and 122 which cooperate with the carriage frame 125 having a shaft 126, wheels 127, and the rails 67a upon the tank wall 68. The carriage frame 125 has also a motor 130, which, through the sprocket wheel 131, actuates 35 by a chain a sprocket wheel 132 and in turn rotates the shaft 126, as seen in Figure 1. This motor 130 has a beidleplate 130a which rests upon this carriage frame 125. This plate 130a also supports the pump 37 and its motor 37a, as seen 40 from Figures 1 and 11.

The deep cleaner can be readily removed from the casing 110 by simply unscrewing the union-members 152 and 153, and then raising a plate 155, to which the pipes are attached. The adjustment of these pipes is carried out by the screw-threaded portions 118 of pipes 40 and nuts 119, and screw-threaded portion 160 and nuts 161 of pipe 44. These adjustments in respect to the plate 155 are made also in respect to the position of the deep cleaner to the filter bed. By this arrangement, the plate 155 can be removed by unloosening the union joints 152 and 153, and the pipes 40 and 44 and deep cleaner as also the removing device, can be bodily removed from 55 the remaining structure, under maintenance of the adjustments. When the deep cleaner is returned in position, the adjustments having been retained, new adjustments are not necessary. This plate 155 and correlated parts are shown in 60 Figure 6 and in Figure 11.

Referring again to Figure 7, the plate 112 is supported by cross-heads 134 which are shown in Figures 2 and 7, and have their ends movable between vertical guide-ways 135 so that the entire cleaning mechanism may be raised or lowered to proper position; these cross-heads also aid to prevent any deflection of cleaner mechanism.

It will be seen from the right hand parts of Figures 1 and 2 and from Figures 6 and 7 that the filter bed, through the action of the plow member 100 and the sprays of the pipe 102, cause a cleansing of the filter bed particles, and the wash water with its impurities is captured by the 75

open ended casing 110 and siphoned out by the removal device 42 and discharged into the laundries 13 at the outlet 45 of the pipe 44.

At the lower end of pipe 44 and below the outlet 45 there is provided a valve operating member of the same construction as described in connection with Figure 5, and this is operated by either striking a cross rod 78 or the spray pipe 85, and as this has been fully described, 10 repetition is not necessary.

The pipe 44, is a structure substantially the duplicate of that described in connection with Figure 3, namely, pipe 33, has a duplicate blind pipe or rod for the purpose of adding strength 15 to the structure.

As the thorough agitation of the entire filter bed as described, and the force of the water and air coming out of the pipe 102 together with natural wear may cause certain particles of sand 20 to be drawn upwardly with the impurities and be siphoned out by the removal device 42, it is proposed to combine with this deep cleaner, a sand replenisher. For this purpose, a sandbox 46 is provided which has openings 46a at its bottom 25 and which holds sand, 46b. The bottom surface of the reticulated bottom is flush or level with the normally desired top surface of the filter bed, but should the level of this filter bed be lowered due to the abstraction of the sand through the removal device, or through wear, sand will then by gravity 30 flow out of the openings 46a and fill up the gap and replenish the sand removed, and thereby restore the normally desired level of the filter bed. 35 This sand container 46 is shown clearly in Figure 1, and in section in Figure 2, and is also indicated diagrammatically in Figure 10.

Transversely of the filter bed, and at one end thereof, is arranged a spray pipe 85 having opening 141 and its end capped by the cap 142, as 40 shown in Figure 2, and in end view in Figure 1. The function of this transverse pipe is to loosen the end part of the filter bed by means of water flow, when replacing the deep cleaner after its 45 removal for repair or inspection, at a position immediately above the spray holes 141. This pipe 85 is placed at one end of the filter bed, and may serve, as described, as an abutment to be impinged by the weighted depending member 77 of the valve shown in Figure 6. When the deep 50 cleaner has been removed and is again replaced in the casing, it first rests on the top of the filter bed. It cannot be forced down into position within the filter bed. It can, however, be brought into proper position, determined by its adjusting 55 nuts 154 on the rods 151 by having the water of the spray pipe pass upwardly through the filter bed, whereby the sand is loosened, and the deep cleaner can then sink down by its own weight.

There is also provided a flush pipe 144 having a 60 manually operated valve 145 which serves to flush out the contents of the tank above the sand bed, should the same be desired. This pipe 144 is connected with an upright pipe 146 terminating in an automatic float control device 147. The level 65 in the tank operates through pipes 144 and 146 the float control device 149. This, in turn, operates by a chain means 148, the starting switch of the motor of the deep cleaner operating carriage. Thereby, the deep cleaner is operated by the head 70 of the water in the tank. The head becomes larger as the filter bed itself needs cleaning.

From the foregoing, it will be seen that a new 75 system of filtration has been provided, which system consists in providing a filtration bed and subjecting the same to periodic surface cleaning

actions and periodic deep cleaning actions, with the replenishment of sand or the like. A device for surface cleaning has been described which consists essentially in the removal from the filter bed of the topmost layer of the filter bed together with the impurities accumulated therein, subjecting the same to an agitating action for the separation of the impurities from the filter bed particles separating such filter bed particles from the impurities, returning the particles to the filter bed 10 and siphoning off the water with the impurities. The operation just described is reversed in its direction at each end of the filter bed, and is operated on time intervals.

Furthermore, the improved method of cleaning 15 a filter bed consists in subjecting all parts thereof locally to agitation and displacement, and while so displacing the particles, subjecting them to the action of an upward stream of water and air for removing the impurities adhering to the 20 particles of the filter bed, and removing the wash water with the impurities from the local habitation of the agitation sphere, and should it be necessary, supplying the filter bed with a replenishment of sand or the like. 25

The improvement also consists in the special structures carrying out this method, in that a plow-shaped or tapering member enters the bottom portion of the filter bed and subjects the 30 portions of the filter bed passing over such plow-shaped device to the impingement of streams of water, or water and air, for removing impurities from the filter bed.

Moreover, an arrangement is provided to remove the pipe 102 should it be necessary to repair or replace, and such removal can be made 35 longitudinally of the plow.

Therefore, the novel principle proposed, as embodied in the invention herein described, is the use of a filter bed of given thickness or depth 40 and suitable length, having a filter medium such as sand, coal, magnetite, or like filter medium, operated upon by two cleaning apparatuses, first an apparatus to clean the top a fraction of an inch of the filter bed at frequent intervals, operating in time cycles as found necessary by test, depending upon the character of the material to be cleaned, and secondly, an apparatus to clean the entire body of sand or filter medium as is found to be necessary, depending again upon 50 the character of the material to be cleaned and determined by the rise of head over the sand and governed by a float switch.

Reference hereinbefore has been made to the fact that all the drawings show the liquid levels 55 about the same height, but the preferable form is to have the level in the tank compartment higher than the level in the launders, whereby a greater head is obtained.

In addition to the cleaning operation, it is important that the sand be kept at a predetermined depth. For this reason, the sand replenisher has been provided which replaces the sand which has been lost due to the cleaning action or natural wear. 65

With each cleaning apparatus, whether surface cleaning or deep cleaning, an off-take by siphoning of the dirty water is provided, with control valves, and a new deep cleaner provision has been made for the wash water to wash the sand 70 by a pump, for instance; this wash water drawing with it air through aspirator pipes to assist in the washing.

For tanks with one hundred running feet of filter bed or less, one surface and one deep clean- 75

er would be sufficient, but on longer tanks, two surface cleaners with one deep cleaner would be provided, with the deep cleaner disposed between the surface cleaners, in which case the surface cleaners would run only from the end of the filter bed to the centre thereof, and back, whereas the deep cleaner would make an entire cleaning cycle.

There is provided on the deep cleaner a box, which is not shown in the drawings, containing a fine screen to prevent the dirt in the wash water, if any, from blocking the fine screen in the cleaner. There is also provided a valve operating a lever controlling a mercoid switch, which in turn controls starting and stopping of the carriage motor, this in order to prevent the carriage movement in the event that the wash water pump is inoperative.

Suitable controls, with starting and reversing switches for the operation of the motors and the carriages, are provided, but as these form no part of the invention, they have not been shown nor described in detail.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations, modifications and adaptations as come within the scope of the appended claims.

What I claim is:

1. In a filtration system, a surface cleaner comprising a shoe resting on the upper portion of the filter bed, a blade wheel adjacent said shoe, and a housing for said blade wheel, open at the lower side thereof and having an outlet at its upper end, whereby the uppermost layer of the filter bed with its impurities is subjected to agitating action, with the impurities passing out of the outlet and the filter bed material returning to the filter bed.

2. In a filtration system, a surface cleaner comprising a shoe having tapered portions, the bottom being horizontal and the sides inclined thereto, in opposite directions, each adapted to enter the filter bed close to its normal upper level, depending on the direction of movement of the surface cleaner, means disposed adjacent said shoe and between the two tapered portions, for moving the water with impurities away from the filter bed, and means for removing said water with impurities from said last named means.

3. In a filtration system, a surface cleaner comprising a shoe of tapering shape adapted to enter the filter bed close to its normal upper level to form a layer of filter bed material over the shoe, a blade wheel adjacent said shoe for agitating the water with impurities in said layer moved by the shoe away from the body of the filter bed, and means for removing said water with impurities from said blade wheel.

4. In a filtration system, having a filter bed, the combination of a surface cleaner comprising a shoe having a horizontal bottom surface and another surface inclined thereto, the tapering ends thereof being adapted to enter immediately below the top surface of the filter bed and separate a layer of filter bed, means adjacent said shoe for removing the impurities with entrained water from said separated top surface layer, means formed of a bottom surface and an inclined surface forming a tapering end for returning the layer to the filter body, said shoe extend-

ing across the filter bed, and means for moving the shoe along the surface of the filter bed.

5. In a filtration system, having a filter bed, the combination in a top surface cleaner of a wedge resting upon the upper portion of the filter bed to separate the uppermost layer from the filter bed, a housing having an outlet to remove from the separated layer the impurities thereof and the water entraining the same, and a blade wheel within the housing for directing the impurities to the outlet of the housing and returning the layer to the body of the filter bed, after being separated from the impurities.

6. In a filtration system, having a filter bed on a sieve, a deep cleaner comprising a shoe having a bottom surface horizontally disposed and a surface upwardly inclined thereto, the tapered edge being adapted to enter the filter bed and to engage the lower portion of the filter bed adjacent the sieve, and means adjacent and at the rear of said shoe for subjecting the portions of the filter bed passing over the shoe, when the shoe moves through the filter bed, to the action of fluid jets, said means being spaced from the shoe to permit the filter bed material to pass therebetween.

7. In a filtration system, a deep cleaner comprising a shoe having a bottom surface horizontally disposed and a surface upwardly inclined thereto, the tapered edge being adapted to enter the filter bed and to engage the lower portion of the filter bed adjacent the sieve, means adjacent and at the rear of said shoe and adjacent the sieve for subjecting the portions of the filter bed passing over the shoe and the sieve, when the shoe moves through the filter bed, to the action of fluid jets, and means for removing the wash water with the impurities from the system.

8. In a filtration system, having a filter bed and a sieve, a deep cleaner comprising a horizontal pipe engaging the lower portion of the filter bed close to the sieve, said pipe having perforations, a wedge shaped member spaced from said horizontal pipe permitting a space between the member and horizontal pipe, vertical means extending upward through the entire depth of the filter bed, and means supplying the vertical means with a fluid, whereby the filter bed directed by the wedge shaped member into said space is acted upon by the fluid passing through the perforations of the horizontal pipe, and the fluid passing through other perforations of the horizontal pipe directs the impurities upwardly.

9. In a filtration system, a filter bed replenisher, consisting of a casing substantially the width of the filter bed for holding filter bed material, and having a plurality of openings in its bottom for releasing said material from said casing, and means for moving said casing along and upon the upper surface of the filter bed to compensate any variations in the normal level of the filter bed, said bottom of the casing being flush with the surface of the normal level of the filter bed.

10. In a filtration system, the combination of a tank having a filter bed, the combination of a surface cleaner having means to remove the top layer of the filter bed, means moving the surface cleaner along the top surface only of the filter bed at certain periods, a deep cleaner having means extending through the body of the filter bed close to the sieve and movable through the body of the filter bed and along the sieve, and

means for moving the deep cleaner at other periods in the filter bed tank.

11. In a filtration system having a filter bed tank, and a launder, the combination of siphoning means for guiding water from said tank to said launder, a control valve in said means disposed in the launder for opening or closing the siphoning means, means for moving the siphoning means from one end of the filter bed to the other, a weighted member for operating said valve and extending therefrom, and stationary means in the path of movement of said control valve in said launder for opening the weighted member of the valve, said means being at least one end of the tank.

12. In a filtration system, the combination of a tank, a filter bed therein, a deep cleaner vertically movable through said filter bed, a stationary perforated pipe transversely across said filter bed at the lowermost portion thereof, and means supplying fluid to said pipe and through said perforations for subjecting the filter material above

the stationary pipe to an ebulliency to permit the deep cleaner seated upon the surface of the filter bed to descend by gravity through the ebullient filter material above said perforated pipe.

13. In a filtration system having a filter medium body and a water layer thereover, a surface cleaner comprising a shoe with horizontal bottom section and concave upper section, said shoe being adapted to be set in the filter medium at a predetermined depth near the upper surface thereof, means for moving said shoe forward and over the filter bed at said depth for passing a layer of filter medium with its entrained water over said shoe, means adjacent said shoe for agitating said separated filter medium to separate the dirty material from the filter medium, means for immediately returning to the filter medium body the separated filter medium to substantially its original position, and means for removing from the system water with the dirty material separated from said separated filter medium.

WILLIAM C. LAUGHLIN.
